Attorney, Agent, or Firm—Quarles & Brady

[57] CLAIM

The ornamental design for a boat, as shown and described.

DESCRIPTION

FIG. 1 is a perspective view taken from the top, front and left side of a boat showing our new design;

FIG. 2 is a left side elevational view thereof, the right side elevational view being a mirror image of the side shown;

FIG. 3 is a top plan view thereof;

FIG. 4 is a front elevational view thereof; and,

FIG. 5 is a rear elevational view thereof.

The dotted line showing of holes in FIGS. 1, 2 and 3 are for purposes of illustration only.
